UNITED STATES PATENT OFFICE.

HENRY ELLSWORTH WOOD, OF DENVER, COLORADO.

ORE-CONCENTRATOR.

1,071,850.

Specification of Letters Patent.

Patented Sept. 2, 1913.

Application filed May 23, 1913. Serial No. 769,368.

To all whom it may concern:

Be it known that I, HENRY E. WOOD, residing at Denver, in the county of Denver and State of Colorado, have invented certain new and useful Improvements in Ore-Concentrators, of which the following is a full, clear, and exact description.

A large class of ore concentrators now in general use is characterized by the presence of an inclined table containing longitudinal corrugations or riffles, on which the wet pulp containing the metallic particles and gangue is flowed from a feed box. A vibratory or vanning motion is imparted to the table transversely to the normal direction of flow, with the result that the solid particles are caused to travel obliquely across the table, the heavier or metal particles following the longest path so that they may be discharged from the table on the end, or in general, recovered at a different point from that at which the gangue is discharged. By the use of such apparatus a distinctive process of separation of the concentrates and gangue is effected, depending entirely upon the relative specific gravities of the different particles, and the vibratory motion to which they are subjected while flowing on the table. In another class of apparatus for the same ultimate purpose of concentration, the ore, in a finely divided and, usually, dry state, is deposited upon the surface of a moving body of water, upon which the metal particles are sustained by surface film tension, so that they may be floated off, while the gangue sinks beneath the surface and is permitted to settle.

The invention, subject of my present application, is primarily designed to increase the capacity and efficiency of ore concentrators in general, by combining in coöperative relation in the same device means for effecting such concentration by both of the processes above described, and to this end it consists in the combination with a concentrating table, of means for feeding thereon the ore to be treated, under conditions conducive to the flotation of the metal particles or slimes, and means for recovering from the table such particles as may be supported by surface film tension, without interfering with the normal operation of the apparatus in the recovery of such concentrates as may sink beneath the surface. With this object in view, I have devised special appliances which may be regarded,

and which will be hereinafter described as attachments to a concentrating table, and while this latter may be of any form or construction that is operative to produce the results hereinafter specified, I have illustrated the invention in connection with a Wilfley concentrating table, as that device is broadly typical of the class, but modified to more perfectly accomplish the objects in view.

In the drawings hereto annexed, Figure 1 is a top plan view of the apparatus complete. Fig. 2 is a rear elevation of the same. Fig. 3 is a view in elevation on an enlarged scale of the device used as a spill-way for the discharge of floating particles. Fig. 3^a is a cross section of the same device, and Fig. 4 is a section on line X—X, Fig. 1.

A represents the table of the well known Wilfley concentrator, having riffles B, and means for imparting to it a vibratory movement transversely to the line of normal flow of the water across the same. In the usual operation of this apparatus, the wet pulp is fed to the table from the feed box C, but in the present case water only is delivered from said box, or any other equivalent means for the purpose, and allowed to flow onto and across the table in a thin stream or sheet. The usual wash water box D is, however, employed and used in the ordinary manner as occasion requires. Immediately over that portion of the table upon which the pulp ordinarily runs from the feed box, there is supported a feed plate E in a frame vibrated by a rod F connected with an eccentric G driven by a pulley H. Above this plate E is a suitable hopper J of any kind that may be adapted to deliver the material in a finely divided and preferably perfectly dry state upon the plate, so that by the latter it is gently and continuously deposited upon the surface of the stream of water issuing from the box C. Extending across the table and slightly above the same, is a pipe K which is to be connected with an air supply of low pressure, and which contains near its outer or lower end a series of perforations through which air jets will issue, in a general direction transverse to the line of flow and toward the feed end of the table, as shown in Fig. 1. Along the edge of the feed end of the table A is a pipe or other suitable conduit P containing perforations and adapted to deliver clear water in jets of regulable pressure between or in

the line of the riffles, and at the lower edge of the table near the corner thereof is an outlet gate L, the opening of which is adjustable both in height and length. Any means for securing this condition may be employed, for example, the discharge opening may be a slot controlled by a vertically adjustable plate M, Fig. 3, and by a horizontally adjustable slide N. There are no other appliances required for the operation of the apparatus than are usually present in devices of this kind.

The operation is as follows: Water is permitted to flow from the feed box C over the table in regulable quantity and in a thin wide stream. When the flow has been established the dry fine ore is deposited by the feed plate, or any other suitable means, upon the surface of this swift, but thin sheet of water. A certain proportion of the metal, as well as the earthy particles, will at once sink into the stream and all such become at once subject to the conditions of concentration which ordinarily obtain in such devices, and pass obliquely over and along the riffles.

A large proportion of the slimes, however, floats upon the surface of the water and these particles are carried by the latter more or less directly across the table and over the riffles thereon toward the spillway or gate L, not being subject to the throw of the table. It will be apparent therefore, since all of the heavier particles of both mineral and gangue are at once arranged in relation to their size and specific gravities in clearly defined straight lines, that there will be a submerged body of ore traveling obliquely across the table, and another body of floating particles passing directly across in the direction of the gate, with the result that there is, theoretically, a triangular area of clear water at the lower corner of the feed end of the table, on which the floating particles flow. For the very mobile surface film

of this body of water the slot in the gate L furnishes an outlet and through this the film flows carrying its load of floating particles into a suitable launder. As the assumed clear water area at the corner will gradually become turbid, it is increased by the jets of clear water issuing from pipe P.

The feed supply from the vibrating plate is liable to deposit some of the floating particles where they will not quite cross the lines of concentrates, gangue and suspended matter as they pass toward the discharge end of the table, the progression being in parallel lines which are oblique to the sides of the table. To offset this effect, air under low pressure from one to two pounds, is directed from the perforations in the pipe K, over the surface of the water so as to force the film loaded with concentrates toward the outlet near the corner. The film responds readily and passes at once to the

clear water area from which it escapes without carrying with it the gangue in suspension.

It is of material advantage to the process described that the riffles for a short distance from and in front of the source of the stream of water be entirely removed, and it is also advantageous to reduce the height, or abruptness of the riffles in the direct line of flow of the floating particles, in order to disturb as little as possible the surface of the water. This feature is illustrated in Fig. 4.

From the nature and purpose of the apparatus above described, it will be evident that the specific character of the concentrator table is not material, and that the construction and arrangement of the several attachments may be greatly varied without departure from the invention. For example, the air pipe K may be of any construction and disposed in any way that will produce the desired result of forcing the surface film toward the gate or outlet and over the clear water area. So also with reference to the character and the means for controlling the water jets for increasing the clear water area, and other features set forth.

It will be understood that the adaptability of the device to the concentration of ores will vary according to the specific character of the latter, for some of these, while capable of concentration by the floating process, require more stable surface conditions than can be practically secured on a table which is not only in motion, but quite sharply inclined. There are, however, many minerals, the floating tendency of which is so strong as to resist the conditions which exist on tables of the type herein described, and for the treatment of all of these the apparatus is of great value and possesses a very high efficiency.

What I claim is:

1. The combination with an inclined vibrating ore concentrating table of the kind described and provided with longitudinal riffles, of means for maintaining a stream of water transversely across the same at the feed end, means for feeding the material to be treated in a finely divided state upon the surface of the stream, a spillway adjacent the feed end of the table to permit the discharge from the table of the surface film of said stream with the particles floating thereon, and means for separately discharging the submerged concentrates and gangue from the table, as set forth.

2. The combination with an inclined vibrating ore concentrating table of the kind described, of means for maintaining a stream of water across the table, means for feeding the material to be treated in a finely divided state upon the surface of the stream, a gate adjacent the feed end of the table and

- opposite the feeding devices, and means for maintaining a flow of clear water over an area adjacent to the gate and transversely to the line of flow of the stream, as set forth.
- 5 3. The combination with an inclined vibrating ore concentrating table of the kind described, of means for maintaining a stream of water across the table, means for feeding the material to be treated, in a finely divided state upon the surface of the stream, a gate adjacent the feed end of the table for the discharge of the surface film with the particles floating thereon, and a source of air under pressure for directing the surface film toward the gate, as set forth.
4. The combination with an inclined vibrating ore concentrating table of the kind described, of a water supply or feed box for maintaining a stream of water across the table, an ore feeding device adapted to deposit the ore in a finely divided state upon the surface of the stream near its source, and an outlet gate at the edge of the table opposite the feeding device, the table being constructed with an area devoid of riffles adjacent the water supply box, and with the riffles in the direct path of the stream modified to reduce disturbance of the surface conditions of the water flowing over them.
- 20 5. The combination with an inclined vibrating ore concentrating table of the kind described, of a water supply box at the higher edge adjacent the feed end of the table and adapted to deliver a thin stream of water upon the same, an ore feeding device adapted to deposit ore in a finely divided state upon the surface of the stream near its source, an outlet gate at the edge of the table opposite the feed device, and a water pipe along the feed end of the table having per-

forations adjacent the outlet gate and adapted to direct jets of water over the table transversely to the normal flow of the stream to the gate.

6. The combination with an inclined vibrating ore concentrating table, of the kind described, of a water supply at the higher edge adjacent the free end of said table, and adapted to deliver a thin stream of water upon the same, an ore feeding device adapted to deposit ore in a finely divided state upon the surface of the stream near its source, an outlet gate at the edge of the table opposite the feeding device, and an air pipe extending over the table and provided with perforations for air jets adapted to direct the surface film of the stream of water toward the outlet.

7. The combination with an inclined vibrating ore concentrating table of the kind described, of means located at the higher edge adjacent the feed end of the table for delivering a stream of water upon the same, an ore feeding device adapted to deposit ore in a finely divided state upon the surface of the stream near its source, an outlet gate at the opposite side of the table adjacent the feed end of the same, a water supply pipe along the feed end of the table provided with perforations near the gate and an air supply pipe with openings therein for directing the surface film of the water stream toward the outlet.

In testimony whereof I affix my signature in the presence of two subscribing witnesses.
